UNITED STATES PATENT OFFICE.

WILLIAM GRUNOW, JR., OF NEW YORK, N. Y.

FOLDING BOX.

1,140,741.

Specification of Letters Patent. Patented May 25, 1915.

Application filed December 3, 1914. Serial No. 875,311.

To all whom it may concern:

Be it known that I, WILLIAM GRUNOW, Jr., a citizen of the United States, residing at New York city, in the county of New York, State of New York, have invented certain new and useful Improvements in Folding Boxes, of which the following is a description, reference being had to the accompanying drawing and to the figures of reference marked thereon.

The invention relates to new and useful improvements in folding boxes, and more particularly to a folding box made from pasteboard, or the like, and which is especially designed for shipping articles by parcel post.

An object of the invention is to provide a folding box, wherein the body portion and the cover may each be made from a single integral blank folded so as to form a structure which is not only non-leakable, but which is strong and durable.

A further object of the invention is to provide a box of the above character with spacers for the articles to be shipped and also with strengthening retainers which not only hold the spacers in place, but which also strengthen the box longitudinally and transversely.

These and other objects will in part be obvious and will in part be hereinafter more fully described.

In the drawings which show by way of illustration one embodiment of the invention: Figure 1 is a perspective view, showing a box embodying my improvements, with the cover separated from the body portion and the upper retainer broken away to show the spacers; Fig. 2 is a longitudinal

sectional view through the box on the line 2-2 of Fig. 3; Fig. 3 is a transverse sectional view on the line 3-3 of Fig. 2; Fig. 4 is a detail in perspective, showing the initial folding of one of the corner flaps; Fig.

5 is a view showing a blank from which either the body portion or the cover may be made; Fig. 6 is a plan view of one of the retainers; Fig. 7 is a sectional view through one of the retainers and the spacers, showing the spacers nested on the depressions in the retainers; and Fig. 8 is a plan view of a blank, showing a strip which may be bent to form one of the spacers.

The invention consists generally in providing a box, wherein the body portion and the cover portion are similar in construc-

tion, the end and side walls of the body portion being of substantially the same height as the end and side walls of the cover. Both the cover and the body portion are made from a single integral blank, which is provided with corner flaps formed integral with the bottom and the side and end walls, so that when the parts are folded a body portion will be formed which is non-leakable. The same is true of the cover portion and this produces a box structure which is especially useful for shipping articles by parcel post.

The corner flaps are foldable against the inner faces of the side and end walls and are also foldable over the top edges of said side and end walls and against the outer faces thereof, which locks the corner and holds the parts of the box in assembled position for use. Located within the box are spacers for spacing the articles to be shipped and these spacers are formed from a strip of cardboard having slots extending from opposite edges thereof and so disposed that when the strip is interlocked at the slots a series of cylindrical cells will be formed. For strengthening the box and for holding the spacers in proper position, retainers are provided, which retainers are preferably made of reinforced card-board. One of the retainers is also formed with depressions for receiving and holding the spacers and these retainers both fit within the body portion of the box and conform to the shape of the box, so as to strengthen the same transversely and lengthwise thereof.

Referring more in detail to the drawings, my improved box consists of a body portion 1 and a cover 2. As above noted, the body portion and cover are both similar in construction and therefore a detailed description of one will answer for the other.

The body portion 1 is formed from a blank indicated at B, Fig. 5. The dotted lines in this figure show the lines of fold in the forming of the box, and said blank folds so as to form side walls 3-3 and end walls 4-4. Formed integral with the bottom portion 5 and the end and side walls are flaps 6. The flaps 6 fold on the line $\alpha-\alpha$ and also on the line $\alpha-\gamma$ and $\alpha-\zeta$, see Fig. 5. Said flap is also provided with a slot 7, which is in line with the points $\gamma-\zeta$, and the flap also folds along this line $\gamma-\zeta$ over the upper edges of the side and end walls, as will be more fully described. The body portion

formed and scored, if desired along the dotted lines indicated in Fig. 5, is first folded so as to bring the parts to the position shown in Fig. 4, with the flap within the side and end walls and the sections 8 and 9 are positioned so that they will fold against the inner faces of the side and end walls 3 and 4. The flap 6 also folds along the center line $x-x$, so that the sections 10-10 will lie 10 against the inner faces of the sections 8 and 9 of the flap forming the corner. The upper section 11 of the flap is then folded over the upper edges of the side and end walls 3 and 4, and this section 11 will lie against 15 the outer faces of the side and end walls 3 and 4, as clearly shown in Fig. 1. The slot 7 is in line with the upper edges of the side and end walls and extends a short distance each side of the central line of fold in the flap. This slot permits the ready turning of 20 the upper section 11 of the flap over the upper edges of the side and end walls and also serves to hold this section of the flap in the position shown in Fig. 1.

25 It will be readily seen that both the body portion and the cover may be quickly folded into assembled position and the parts held therein by the construction of the blank itself without any other locking devices. It will also be readily seen that both the body portion and the cover, when 30 in folded or assembled position, are non-leakable.

Located within the box is a series of spacers 12. Each spacer is formed from a single strip, as indicated at S, Fig. 8. This strip is provided with slots 13, 14, 15 and 16 extending inwardly from one edge of the strip to a point centrally of the strip and slots 17, 18 and 19 extending inwardly from the other edge of the strip to points centrally of the strip. This strip is then bent so that the slot 13 may be interlocked with the slot 18 and the slot 14 is interlocked 40 with the slot 17. The sections of the strip between the slots 14 and 17 form a cylindrical cell 20, while the sections of the strip between the slots 13 and 14 form one-half of the cell 21, while the sections of the strip 45 between the slots 17 and 18 form the other half of said cell. The other end of the spacer is similarly formed by bending the strip and the two ends of the strip 22 and 23 meet centrally of the spacer, as clearly 50 shown in Fig. 4. When the slot 13 engages the strip at the slot 17, it will be understood that the slot 13 engages the solid portion of the strip at the end of the slot 17, while the slot 17 engages the solid portion 55 of the strip at the end of the slot 13, so that when the strip is bent to form these cells it is bent back upon itself and the edges at each side lie in the same plane.

In order to hold the spacers in proper 65 position in the box and also to strengthen

the box, I have provided retainers, and the retainer 24 is formed preferably of corrugated card-board and this corrugated card-board is put under pressure so as to form depressed portions 25, 26 and 27. These 70 depressed portions are similar in contour to the outer walls of the spacers and the spacers are adapted to nest in the depressions in this retainer 24. The retainer 24, as to length and width, is of the same proportions as the length and width of the inside of the body portion of the box, and this retainer 24, with the depressions therein, is placed in the bottom of the box. The spacers are then placed in the depressions 75 in the retainer after which a second retainer 28, as shown in Fig. 1, is placed on top of the spacers. The spacers are preferably of such a height that when the retainer 28 is placed thereon, the outer face of said retainer is flush with the outer edge of the box, so that the retainer is wholly within 80 the upper edges of the box, and, therefore, as said retainer fits closely to the side and end walls of the box, said box will be strengthened 85 lengthwise and laterally thereof.

When the cover is in place on the box, the retainers and spacers will be held in assembled position. The spacers are preferably so constructed that they are separate from each other and the retainers will hold the spacers in this separated position.

90 My improved box is particularly adapted for shipping eggs by parcel post. An egg is placed in each single cell and these 100 spacers hold the eggs completely separated from each other.

95 It is obvious that minor changes in the details of construction and arrangement may be made without departing from the 105 spirit of the invention, as set forth in the appended claims.

Having thus described my invention, what I claim as new and desire to secure by Letters Patents, is:

110

1. A folding box comprising a bottom, side and end walls, and corner flaps formed integral with said bottom, side and end walls, said flaps being foldable against the inner face of the side and end walls, and having a portion foldable over the upper edge of said side and end walls and against the outer faces thereof, each of said flaps having a slot formed therein in line with the upper edges of the side and end walls 115 and extending a short distance each side of the central line of fold in the flap.

120 2. A folding box comprising a body portion and a cover, said body portion and cover being similar in construction and having the side and end walls thereof substantially the same height, said body portion including a bottom, side and end walls and corner flaps formed integral with said bottom, side and end walls, said flaps being 125

130

- foldable against the inner faces of the side and end walls and having a portion foldable over the upper edges of said side and end walls and against the outer faces thereof, each of said flaps having a slot formed therein in line with the upper edges of the side and end walls and extending a short distance each side of the central line of fold in the flap.
- 5 3. The combination of a box, of spacers located therein for articles to be shipped, said spacers comprising a strip of cardboard having slots adjacent each end and leading from the same edge substantially half way across the strip and a slot at the
- 10 center of the strip leading from the opposite edge substantially half way across the strip, and having also interlocking slots between the end slots and center slot, said strip being bent and interlocked at the slots 20 to form cylindrical cells for the articles to be shipped, the end slots being interlocked with the middle slot.
- 15 In testimony whereof, I affix my signature, in the presence of two witnesses.
